[57] CLAIM

The ornamental design for an exterior surface configuration of a motor vehicle lever, as shown and described.

DESCRIPTION

FIG. 1 is a perspective view from the right of an exterior surface configuration of a motor vehicle lever according to my novel design;

FIG. 2 is a perspective view from the left of an exterior surface configuration of a motor vehicle lever according to my novel design; and,

FIG. 3 is a perspective view from the top of an exterior surface configuration of a motor vehicle lever according to my novel design.

The broken lines shown in all drawing views are for illustrative purposes only and form no part of the claimed design.
